[57] CLAIM

The ornamental design for kingpin lock, as shown and described.

DESCRIPTION

FIG. 1 is a perspective view of the kingpin lock of the present invention.

FIG. 2 is a left-side view of the kingpin lock of FIG. 1.

FIG. 3 is a right-side view of the kingpin lock of FIG. 1.

FIG. 4 is a front view of the kingpin lock of FIG. 1.

FIG. 5 is a rear view of the kingpin lock of FIG. 1.

FIG. 6 is a top view of the kingpin lock of FIG. 1; and,

FIG. 7 is a bottom view of the kingpin lock of FIG. 1.

The broken lines shown in all views are for illustrative purposes only and form no part of the claimed design.
